[57] CLAIM

The ornamental design for a table base, as shown and described.

DESCRIPTION

FIG. 1 is a perspective view of a table base showing my new design;

FIG. 2 is a front elevational view;

FIG. 3 is a top plan view thereof;

FIG. 4 is a bottom plan view thereof;

FIG. 5 is a perspective view of a second embodiment of table base constructed in accordance with this invention; and

FIG. 6 is a perspective view of a third embodiment of table base constructed in accordance with this invention.

The table top illustrated by means of broken lines in FIG. 2 has been shown for illustrative purposes only. The side and rear elevation views of the embodiment shown in FIGS. 1-4 is the same as the front elevation view thereof shown in FIG. 2. The front, top, bottom, side and rear views of the embodiments of FIGS. 5 and 6 are the same as for the embodiment shown in FIGS. 1-4 except for the surface ornamentation thereof.
